UNITED STATES PATENT OFFICE

163,483

GAS-FIRED UNIT HEATER OR SIMILAR ARTICLE

Charles A. Reichelderfer, Herman G. Raymer, and Harold L. Herzog, Columbus, Ohio, assignors to Norman Products Company, Columbus, Ohio, a corporation of Ohio

Application November 8, 1950, Serial No. 12,906

Term of patent 14 years

(Cl. D81—10)

To all whom it may concern:

Be it known that we, Charles A. Reichelderfer, Herman G. Raymer, and Harold L. Herzog, citizens of the United States, residing at Columbus, in the county of Franklin and State of Ohio, have invented a new, original, and ornamental Design for a Gas-Fired Unit Heater or Similar Article, of which the following is a specification, reference being had to the accompanying drawing, forming a part thereof.

Fig. 1 is a top plan view of a gas-fired unit heater or similar article, showing our new design;

Fig. 2 is a bottom plan view;

Fig. 3 is a front side elevational view; and

Fig. 4 is a rear side elevational view thereof.

We claim:

The ornamental design for a gas-fired unit heater or similar article, substantially as shown.

CHARLES A. REICHELDERFER.

HERMAN G. RAYMER.

HAROLD L. HERZIG.
